HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SAFETY SWITCH MECHANISM.

1,342,219.

Specification of Letters Patent. Patented June 1, 1920.

Application filed June 6, 1918. Serial No. 238,501.

To all whom it may concern:

Be it known that I, HUBERT F. KRANTZ, residing at Brooklyn, in the county of Kings and State of New York, have invented certain new and useful Improvements in a Safety Switch Mechanism, of which the following is a specification.

This invention relates to a safety switch mechanism, and the object of the invention 10 is to provide an arrangement particularly adapted for the proper and safe control of motor and like circuits.

A more particular object is to provide means adapted to prevent the breaking of 15 a motor circuit by other than the switch installed for that purpose.

A further object is to provide, in combination with a motor starting, or circuit controlling, switch and a line-disconnecting 20 switch, safety means to prevent "off" movement of the line-disconnecting switch at any time while the circuit controlling switch is "on".

A further object is to provide, in the 25 above combination, a guard member for the live parts of the line-disconnecting switch mechanism and to arrange the safety means just referred to in such manner that it will serve to prevent movement of said guard member out of guarding position while the 30 circuit controlling switch is "on".

A further object is to provide the guard member with connections such as to cause the line-disconnecting switch to move "off" 35 when the guard member is being displaced, and to arrange the safety means in such manner that said connections are not operable to move the line-disconnecting switch "off" while the circuit controlling switch 40 is "on".

A further object is to provide the guard member with retaining means and to arrange the safety means in a manner to prevent said retaining means from being released while the circuit controlling switch 45 is "on".

Other objects and aims of the invention more or less specific than those referred to above, will be in part obvious and in part 50 pointed out in the course of the following description of the elements, combinations, arrangements of parts and applications of

principles, constituting the invention, and the scope of protection contemplated will be indicated in the appended claims.

In the accompanying drawings which are to be taken as a part of this specification, and in which I have shown merely a preferred form of embodiment of the invention:

Figure 1 is a diagrammatic view illustrating a system, or arrangement of elements in conformity with this invention, and

Fig. 2 is a longitudinal sectional view, 65 partly in elevation, of the line-disconnecting switch mechanism suggested as present in Fig. 1.

Motor circuits, as now commonly installed, include two distinct switch devices 70 for controlling the supply of current from the mains to the motor: first, a circuit controlling switch, and second, a line-disconnecting switch. The former is of such a type as to be capable of successfully and 75 safely breaking the circuit even under very heavy overload, while the latter is not of this capacity but is only intended for mechanically disconnecting the circuit controlling switch from the mains at a time when 80 no current is flowing through the circuit controlling switch.

The line-disconnecting switch is of a capacity only sufficient to carry the normal amount of current during the operation of 85 the motor and should never be used for breaking the running circuit.

The present device is primarily a means to positively prohibit use of the line-disconnecting switch as a circuit breaker.

Referring to the drawings for describing the elements suggested therein, the reference character L indicates the line-disconnecting switch, while the reference character G indicates the circuit controlling, or 95 motor starting, switch. The reference character H indicates the motor.

The circuit represented includes wires 1 and 2, which may be considered as the mains. These enter the housing 3 of the line-disconnecting switch at one end thereof. From the opposite end of the housing 3 wires 4 and 5 continue to, and enter the housing 6 of the circuit controlling switch. From the

opposite side of the housing 6 of the circuit controlling switch wires 7 and 8 lead to the motor H. The switch mechanisms L and G are preferably contained within housings as illustrated, and there may be other features associated with them, such for instance the fuses 9 and 10.

5 The operating handle, as 11, of the line-disconnecting switch is operable to swing the double ended switch blades 12 for connecting the terminals 13—14 and 15—16 together.

10 The operating handle, as 17, of the circuit controlling switch is adapted to swing the switch blades 18 for controlling circuit between the contacts 19—20 and 21—22.

15 At 23 is indicated a solenoid coil having a movable core 24 and being connected by wires 25 and 26 with the wires 7 and 8 respectively. By the connection of this coil in shunt in the circuit at a point between the circuit controlling switch G and the motor, it is apparent that whenever current is flowing in the circuit the coil is energized.

20 Whenever the coil is energized the head 27 at one end of the core 24 is thrust outwardly and is maintained in its outer position, as shown by the dotted lines in Fig. 1, as long as the coil remains energized.

25 30 When the head 27 is in its outer position it is intended to stand in a position to obstruct "off" movement of the switch L.

The construction of the switch L, as shown in Fig. 2, is illustrated for example 35 as being similar to that disclosed in my pending application Serial No. 175,191, and includes a plunger-like part 28 which is connected with a blade operating toggle 29 in such manner that when the toggle is made, 40 and the switch blades 12 are moved "on," as by swinging of the handle 11, the part 28 is in a projected position as shown by the dotted lines in Figs. 1 and 2, and must necessarily be withdrawn from this position to 45 the position shown in full lines whenever the toggle is broken. Thus while the switch blades 12 are "on" the part 28 is projected, while whenever the switch blades are "off" the part 28 is withdrawn.

50 55 50 A projection 29 is formed upon the part 28. This projection provides a rearwardly facing shoulder 30 and the head 27 of the core of the coil is adapted to stand, when the coil is energized, behind this shoulder so as thus to prevent movement of the part 28 from its projected position.

Whenever, therefore, the current is flowing in the wires 7 and 8, and the coil 23 is thereby energized, it is impossible to withdraw 60 the part 28 for breaking the circuit by the switch L. The operator's efforts to swing the handle 11 "off" will be resisted by engagement of the surface 30 against the head 27 and before he can succeed in swinging the handle 11 he must necessarily first

break the circuit at the switch G so as to make dead the wires 7 and 8 and deenergize the coil 23.

As above suggested, in association with the parts thus far described, this invention 70 includes the provision of a guard member, for preventing access to live parts of the line-disconnecting switch. As illustrated, this guard member includes a door, as 31, pivotally mounted, as at 32, as a part of the 75 housing 3. A part 33 is provided concentric with the pivot 32 adapted to move into position in front of the member 28 whenever the door is open.

The part 33 is provided with a surface 80 portion 34 which stands to engage the upper surface of the head 27 when said head is in its outer position. The head 27 thereby serves to prevent any opening movement of the door while the coil is energized. A 85 latch 35 is provided at the free edge of the door operable to move into and out of locking position beneath a stationary portion 36 of the housing. A link 37 extends into proximity with the part 28 so as to prevent 90 unlocking of the latch whenever the part 28 is in the projected position as suggested in my pending application Serial No. 158,957.

It will be noted that, since the part 28 must be in its projected position whenever 95 the head 27 is projected, then the head 27, acting to positively prevent return movement of the part 28 also serves at the same time to positively prevent unlocking movement of the latch 35. The door, or guard 100 member, 31 may thus not even be unlocked while current is flowing to the motor.

As many changes could be made in this construction without departing from the scope of the invention as defined in the following claims, it is intended that all matter contained in the above description or shown in the accompanying drawings, shall be interpreted as illustrative only and not in a limiting sense.

Having thus described my invention, what I claim as new and desire to secure by Letters Patent is:

1. In an electric circuit, the combination with two inclosed switches connected at different points in said circuit, of means adapted to prevent the opening of the inclosing casing of one of said switches prior to an "off" movement of the other switch.

2. In an electric circuit, the combination with two switches connected at different points in said circuit and inclosing casings for the switches, of electrically operable means connected in shunt relation to the said circuit and adapted to prevent the opening of one casing prior to an "off" movement of the other switch.

3. In a motor circuit, the combination with a circuit-controlling switch and a line-disconnecting switch having an inclosing

casing, of means adapted to prevent an "off" movement of the line-disconnecting switch and the openings of the inclosing casing thereof prior to an "off" movement of the 5 circuit-controlling switch.

4. In a motor circuit, the combination with a line-disconnecting switch having an inclosing casing and a circuit-controlling switch, each movable into "on" and "off" 10 positions, of obstructing means adapted to prevent operation of the line-disconnecting switch into one of its positions and opening of the casing, and means whereby the effectiveness of said obstructing means is dependent upon the position of the circuit-controlling switch.

5. In a motor circuit, the combination with a line-disconnecting switch having an inclosing casing, and a circuit-controlling 20 switch, the latter being installed between the line-disconnecting switch and the motor, of electrically operable means connected in shunt relation to the circuit between the circuit-controlling switch and the motor to prevent "off" movement of the line-disconnecting switch and opening of the inclosing 25

casing thereof except when the circuit-controlling switch is "off."

6. In an electric circuit, the combination with two switches connected at different 30 points in said circuits, and removable guard means for guarding certain parts of one of said switches, of means adapted to prevent removal of said guard means except when the second switch is "off." 35

7. In an electric circuit, the combination with two switches connected at different points in said circuit, removable guard means for guarding certain parts of one of said switches, and connections whereby to 40 cause "off" movement of said mentioned switch whenever said guard means is removed, of means adapted to prevent operation of said connections and to retain the guard member in guarding position except 45 when the second switch is "off."

In testimony whereof I affix my signature in the presence of two witnesses.

HUBERT F. KRANTZ.
